ALBERT H. STEBBINS, OF LOS ANGELES, CALIFORNIA.

AIR CLASSIFIER.

Application filed February 1, 1927. Serial No. 165,071.

This invention relates to multiple treatment air classifiers adapted for use in separating fine dust-like materials.

These fine dust-like particles are hard to separate because they tend to cling together and will not settle rapidly out of the air in which they are carried. It is therefore desirable to employ centrifugal force either alone, or in combination with gravity, to promote the separation of the very fine particles from the slightly larger particles, and in order to effect a complete classification the materials should be subjected repeatedly to the separating forces.

15 The present invention is therefore directed to an air classifier which is so constructed that air bearing the materials to be treated is caused to travel along a tortuous path at high speed with the result that the heavier particles are thrown outwardly by centrifugal force toward the outer wall of the loops or bends. This removes the larger particles from the air traveling near the inner wall of the loops or bends so that the air and finer particles traveling near the inner curved wall of these loops or bends may be removed from the conduit without the heavier particles. In this manner the lighter particles are gradually removed from the 25 conduit while the coarser particles remain therein throughout the classifying operation.

One of the features of the present invention resides in the construction whereby the size of the tortuous conduit having the loops or bends above mentioned is gradually decreased from one end toward the other to accommodate the gradual decrease in the volume of the air traveling lengthwise of the conduit. This decreasing in air volume is produced by withdrawing the air and finer particles traveling near the inside of the loops from the conduit while the larger particles remain in the conduit for further treatment.

Another feature of the invention resides in the construction whereby two or more multiple treatment classifiers of the type that taper from one end toward the other are connected in series.

The various features of the invention and novel arrangement of parts will be best understood from the accompanying drawings when read in connection with the following description.

In the drawings—

Fig. 1 is a vertical sectional view through a classifier constructed in accordance with the present invention;

Fig. 2 is a rear elevation of the classifier of Fig. 1;

Fig. 3 is a sectional view taken on the line 3—3 of Fig. 1;

Fig. 4 is a vertical sectional view through a modified type of classifier;

Fig. 5 is a side view of a portion of the classifier of Fig. 4, the side wall being partly broken away; and

Fig. 6 is a vertical section view of a further modified construction.

The classifier of the present invention is preferably supported in an upright position and may be operated either by suction or by an air blast, or by the combination of suction and air blast; but in many cases the use of suction alone will be desirable because if the materials being treated are carried lengthwise of the classifier by suction they will exert a less wearing and cutting action upon the walls thereof than they will if they are carried through the classifier by an air blast. The present invention may be given various embodiments, and one good construction is shown in Figs. 1, 2 and 3, wherein the entire classifying operation is effected within the tortuous conduit 10 which is shown as gradually decreased in size from its upper towards its lower or discharge end. In the construction shown the operation of the classifier is effected by exhausting air from the conduit 10 at various points along its length. This serves to draw air into the conduit at its upper end where the materials to be treated are introduced into the path of the air by the discharge hopper 11 having the adjustable gates 12 for controlling the rate of flow of the materials to the conduit 10 from the feed hopper.

The conduit 10 is provided with a series of loops or bends, as will be apparent from the drawings, and means is provided for exhausting air from the conduit at the inner side of these loops or bends. In the construction shown the air exhaust means consists of the pipes 13 disposed at the inner side of the loops and arranged to extend transversely of the tortuous conduit. Each exhaust pipe 13 has an air inlet opening or slot 14 disposed near the upper end of a passage 15 leading from the inner curved

portion of a loop or bend of the tortuous conduit. Air is exhausted from the pipes 13 by means to be described, and this serves to draw air into the upper end of the conduit 10 through the air inlet opening 16. In order to prevent the materials from becoming clogged at the lower end of the discharge hopper 11 it may be desirable to provide the lower portion of this hopper with the air inlet apertures 17 which are arranged so that some of the air entering the conduit 10 will pass through the apertures 17 to promote the flow of materials into the conduit from the discharge end of the hopper.

15 Air is exhausted from the opposite ends of the exhaust pipes 13 by providing the air exhaust receptacles 18 at the opposite sides of the conduit 10. These receptacles are preferably made relatively large so that the 20 larger particles that enter these receptacles will have an opportunity to settle therein and collect in the lower ends 19 of each receptacle from which they may be withdrawn from time to time. Air is exhausted from 25 the upper ends of the receptacles 18 by providing the exhaust pipe 20 which is connected to the receptacles 18 by the branch pipes 21, and the pipe 20 leads to an exhaust fan 22. The rate at which the air is exhausted 30 from the receptacles 18 may be controlled by adjusting the gate or valve 23 mounted in the pipe 20.

The air exhaust means described will cause the air and materials to be treated that enter the upper end of the conduit 10 to travel lengthwise thereof at high speed. This will cause the larger particles to be thrown outwardly by centrifugal force towards the outer wall of the loops or bends 24, with the 40 result that the larger particles are removed from the air traveling near the inner wall of the loops or bends, and it is therefore possible to remove the finer particles from the classifier without removing the larger particles by extracting from the classifier the air and finer particles traveling near the inner wall of the loops of the conduit. Since air is exhausted from the conduit 10 at various points along its length the volume of 45 air within the conduit will gradually decrease towards the lower end of the classifier. It may therefore be desirable to give the conduit the tapered construction shown so that it gradually decreases in size from 50 its upper to its lower end to accommodate the gradual decrease in the volume of the air within the conduit. The larger particles which remain within the conduit throughout the treatment are discharged at the lower 55 end 25 thereof into the closed receptacle 26 which may extend a substantial distance downwardly below the discharge end of the conduit, as shown, and portions of this receptacle may also extend upwardly at either 60 side of the tortuous conduit, as will be ap-

parent from Fig. 1. The air which enters the receptacle 26 through the discharge opening 25 with the larger particles may be removed from the upper end of the receptacle 26 by providing the exhaust openings 70 27 which lead into the exhaust receptacles 18 disposed at the opposite sides of the conduit. By making the receptacle 26 relatively large as shown the heavier particles 75 will have ample opportunity to collect in the lower end 28 thereof so that they may be withdrawn from time to time.

The entire air classifier may be constructed of sheet metal and the tortuous conduit 10 may be formed by providing the tortuous 80 walls 24 the marginal edges of which may be secured to the inner side walls 29 of the receptacles 18 and these receptacles may be provided with the outer side walls 30. The opposite ends of the exhaust pipes 13 extend 85 through the inner side walls 29 and these pipes may be formed by giving them the spiral construction shown, wherein it will be seen that each pipe has the curved portion 31 which forms part of the tortuous conduit 90 and also forms the upper wall of the air exhaust passage 15. It may be desirable to omit the exhaust slot from the uppermost pipe 32 of the conduit and the same is true 95 of the pipe 32 adjacent the lower end of the conduit 10.

The distance between the adjacent pipes 13 near the lower end of the conduit will be quite small, say not over two inches apart, and the distance between the pipes 13 near 100 the upper end of the conduit may not be more than several inches so that the successive loops or bends 24 of the conduit will be relatively small, and a conduit having a large number of loops or bends may be provided 105 within a classifier that is only a few feet in height. It will therefore be seen that a large number of successive treatments may be effected in a relatively small classifier.

If it should be desired to subject the materials to be classified to a greater number of treatments than can be effected in the tapered construction shown in Fig. 1, it may be desirable to employ the modified construction of Fig. 4 wherein two or more classifiers such as shown in Fig. 1 are connected in series so that when the coarser particles reach the discharge opening 25 of the construction shown in Fig. 4 they are not delivered into a settling chamber 26, as in Fig. 1, but are directed into a second tortuous classifier 33 which may be similar in construction to the classifier through which they have just passed. Air for carrying the materials through the second tortuous conduit 110 33 may be introduced through the air inlet passage 34 and air may be exhausted from the entire series of exhaust pipes 13 of Fig. 4 by providing the upper portion of this classifier with the exhaust receptacles 18 the 115 120 125 130

lower ends of which receptacles are connected to the exhaust receptacles 35.

It will be understood from the foregoing description and from the drawings that air from the atmosphere is introduced into the tortuous conduit 10 only at the upper end thereof and is not introduced at various points lengthwise of the conduit, with the result that a closed construction is provided which might well be connected to a dust producing device from which it is desired to exhaust dust-laden air. Having this use of the present invention in mind a modified construction is shown in Fig. 6 wherein the feed hopper 11 has been omitted, and the upper end of the tortuous conduit 10 is provided with a feed or suction pipe 36 which may lead from the upper portion of a concentrator deck or from various other dust-producing devices.

A multiple treatment classifier having the construction herein described, while small and compact, has a large capacity due to the continuous flow of air and materials to be treated through the tortuous conduit at high speed, and it utilizes the separating action of centrifugal force to a high degree considering the small size of the loops of the conduit. The operation of this novel classifier requires very little attention on the part of the machine attendant, and the large number of treatments to which the materials may be subjected serve to completely remove the finer from the slightly larger particles, while the high speed at which the air and materials travel within the conduit prevents clogging.

While the multiple treatment classifier of the present invention is designed more particularly for the use of air as a carrying medium for the particles to be separated, and the specification and claims are directed to the air treatment, nevertheless water may be successfully employed as the carrying medium in a classifier having the novel construction of the present invention. When water constitutes the carrying medium the stream of water and ore pulp will pass downwardly in the tortuous passage 10 and if this relatively heavy carrying medium exercises a substantial floating or semi-floating effect on the lighter materials to be separated from the heavier materials, then the water lying at the upper surface of the stream traveling within the passage and the floating particles may be removed through the discharge slots 14, while the heavier particles which do not rise to the surface will be delivered as tailings into the hopper 26.

What is claimed is:—

1. A multiple treatment classifier, comprising in combination, a tortuous conduit that gradually decreases in size from one end toward the other and provided with a series of bends or loops, means for introduc-

ing air and the materials to be treated into the larger end of the conduit to travel lengthwise thereof at high speed so that the heavier particles will be thrown outwardly by centrifugal force toward the outer wall 70 of the loops, exhaust pipes mounted transversely of said conduit within the bends of the loops and provided with longitudinally extending slots arranged to exhaust from the conduit the air traveling near the inner wall of the loops and from which the heavier particles have been removed by centrifugal force, and each slot being positioned to face away from the main path of the air traveling within the conduit. 80

2. A classifying unit consisting of a plurality of multiple treatment classifiers connected in series so that one classifier discharges into the next to retreat the materials, and each classifier, comprising in combination, a tortuous conduit that gradually decreases in size from one end toward the other and provided with a series of bends or loops, means for introducing air and the materials to be treated into the larger end 90 of each conduit to travel lengthwise thereof at high speed so that the heavier particles will be thrown outwardly by centrifugal force toward the outer wall of said loops, and means for removing from each conduit at the inner side of the loops the air which has been freed from the heavier particles by centrifugal force. 95

3. A multiple treatment classifier, comprising in combination, a tortuous conduit having a series of bends or loops, exhaust pipes extending transversely of the conduit and arranged to exhaust air adjacent the inner wall of the loops or bends, air exhaust receptacles disposed at the opposite sides of the conduit for exhausting air from said pipes and conduit, means for introducing air and the materials to be treated into the upper portion of the conduit to travel lengthwise thereof at high speed so that the heavier particles will be thrown outwardly by centrifugal force toward the outer wall of said loops, and a closed receptacle for receiving the heavier particles discharged from the lower end of said conduit and provided with settling compartments that extend along the conduit adjacent its remaining two sides. 110

4. A multiple treatment classifier, comprising in combination, a tortuous conduit that gradually decreases in size from one end toward the other and provided with a series of bends or loops, means for introducing air and the materials to be treated 120 into the larger end of the conduit to travel lengthwise thereof at high speed so that the heavier particles will be thrown outwardly by centrifugal force toward the outer wall of the loops, exhaust pipes mounted 125

transversely of said conduit within the bends of the loops and provided with openings for exhausting from the conduit the air traveling near the inner wall of the loops, air exhaust receptacles disposed at the opposite sides of the tortuous conduit for exhausting air from the opposite ends of the pipes, and said openings being positioned to face away from the main path of the air traveling within the conduit.

5. A multiple treatment classifier, comprising in combination, a tortuous conduit that gradually decreases in size from one end toward the other and provided with a series of 10 bends or loops, exhaust pipes extending

transversely of the conduit within the loops and each pipe having an inlet opening formed in its upper side and a settling passage leading from the inner curved side of the conduit to said opening, means for introducing air and the materials to be treated into the larger end of the conduit to travel lengthwise thereof at high speed so that the heavier particles will be thrown outwardly by centrifugal force toward the 20 outer wall of the loops, and means for exhausting air from said pipes.

25 In testimony whereof, I have signed my name to this specification.

ALBERT H. STEBBINS,
